UNITED STATES PATENT OFFICE.

WILLIAM E. SPARKS, OF NEW BRITAIN, CONNECTICUT, ASSIGNOR TO THE KEMPSHALL MANUFACTURING COMPANY, OF SAME PLACE.

DESIGN FOR A SASH-FASTENER FRAME.

SPECIFICATION forming part of Design No. 14,972, dated April 22, 1884

Application filed September 17, 1883. Term of patent 7 years.

To all whom it may concern:

Be it known that I, WILLIAM E. SPARKS, a citizen of the United States, residing at New Britain, in the county of Hartford and State of Connecticut, have invented and produced a new and original Design for Sash-Fastener Frames, of which the following is a description, reference being had to the accompanying drawing, forming a part thereof.

- 10 A designates the circular box-like elevation for the base-plate, truncated upon one side, and *a a* designate lateral wings. My base-plate carries an ornamentation upon its entire wall, except upon its truncated portion, such 15 ornamentation consisting of vertical indentations or grooves, as shown; but this ornamentation may be omitted, as it is not essential to my design, which consists in the configuration of the base-plate having the projecting screw- 20 plates, one upon each side of the frame. As

shown, these projections are just back of the line of truncation. The said plates are flush with the bottom of the frame, and rise only about one-half as high as the thickness of the frame, as shown, thus giving an elevation to 25 the entire frame in its complete circle. This is the distinguishing feature of my design.

What I claim and desire to secure by Design Letters Patent, is—

The design for a sash-fastener frame, consisting of the base-plate provided with the laterally-extending ears, projecting from the same just back of the line of truncation, and flush with the bottom thereof, rising to about one-half the thickness of the base-plate, as shown 30 and described.

WILLIAM E. SPARKS.
